DESIGN FOR A MANICURIST'S TABLE TOP

Billie B. Gaitskill, Los Angeles, Calif.

Application November 21, 1946, Serial No. 134,990

Term of patent 7 years

(Cl. D33—14)

To all whom it may concern:

Be it known that I, Billie B. Gaitskill, a citizen of the United States, residing at Los Angeles, in the county of Los Angeles and State of California, have invented a new, original, and ornamental Design for Manicurist's Table Top, of which the following is a specification, reference being had to the accompanying drawings, forming part thereof, in which:

Fig. 1 is a perspective view of a manicurist's table top, embodying my new design;

Fig. 2 is an exploded perspective view of the top surface section and its supporting frame in separated relationship and omitting the lamp, the covers for the respective compartments being shown in open position;

Fig. 3 is a front side elevation of the top section, omitting the frame and lamp;

Fig. 4 is a rear side elevation of the top section shown in Fig. 3.

I claim:

The ornamental design for a manicurist's table top, as shown.

BILLIE B. GAITSKILL.
